UNITED STATES PATENT OFFICE

2,421,491

SIGNAL FLARE MAGAZINE AND CASTER

John A. Gearon and Edward Gearon,
Chicago, Ill.

Application December 26, 1944, Serial No. 569,899

3 Claims. (Cl. 89—1)

1

Our invention relates to a magazine for storing and releasing signal flares.

Among the objects of our invention is to provide a device for storing a quantity of flares arranged in suitable position so that they may be protected from the elements, and where they are needed for warning purposes that they may be quickly ignited and presented to view outside the container at the bottom thereof. If found necessary to continue the warnings, it is possible to repeat the operation until all the flares are used. If the nature of the danger requires the dropping of the flares at intervals of travel, the same may be accomplished by the means provided.

Another important feature of this device is to provide means for casting or pressing a flare onto a railway rail or onto a public highway from transportation vehicles, such as railway cars or locomotives or motor engines, or from automobiles, buses or trucks, while such vehicles are moving at any rate of speed.

Our invention also contemplates such other objects, advantages and capabilities as will later more fully appear and which are inherently possessed by our invention.

While we have shown in the accompanying drawings a preferred form of our invention, yet we wish it understood that the same is susceptible of modification and change without departing from the spirit of our invention.

Referring to the drawings, Fig. 1 is a side elevational view of our flare magazine; Fig. 2 is a front elevational view of the same; Fig. 3 is a top plan view with a portion broken away to show motor mechanism; Fig. 4 is an enlarged detailed sectional view on line 4—4 of Fig. 3; Fig. 5 is an enlarged front elevational view of our rack assembly and tubes; Fig. 6 is a side elevational view of the structure shown in Fig. 5; Fig. 7 is a detailed sectional view on line 7—7 of Fig. 1; Fig. 8 is a vertical sectional view on line 8—8 of Fig. 1 partly broken away to show the rack in operation; Fig. 9 is an enlarged sectional view of the operating mechanism with wiring diagram; Fig. 10 is a detailed view showing our device attached to the rear truck of a railroad car; Fig. 11 is a detailed sectional view of railroad wheel and track showing our flare being held to rail, after being cast thereon; and Fig. 12 is a detailed view showing our device attached to the rear bumper of an automobile.

The embodiment selected to illustrate our invention comprises a housing 10 having closed top, front and sides. Within our housing are front and rear compartments 11 and 12 respec-

2

tively. Movable positioned within front compartment 11 is rack 13 having a plurality of vertically spaced shelves 14 to receive the body portions 15 of flares 16. Attached to the rear wall 17 of rack 13 are a plurality of spaced tubes or barrels 18 projecting forwardly on a line with the center of the shelves 14 so as to receive the hollow handles 19 of flares 16. Rear wall 17 has a plurality of inwardly bent portions 39 to receive and hold a cartridge 40.

The rear wall 17 of rack 13 has a plurality of vertically spaced pairs of parallel openings 20, each pair adapted to receive teeth 21 of a pair of parallel gears 22 housed within rear compartment 12. Gears 22 are operated through gear reduction 23 by motor 24 which is supported by straps 25 attached by ears 26 to the rear wall 27 of rear compartment 12.

Adjacent the rear of shelves 14 is a vertically extending plate 28 having in its opposite side edges a plurality of notches 29; these notches 29 are adapted to removably receive fingers 30 of detents 31 which are attached to the side walls 32 of compartment 11. Detents 31 each have a housing 33 within which is positioned a spring 34 adapted to normally hold finger 30 in extended position. Each of fingers 30 has a head 35 extending beyond the housing 33 for manual operation.

Attached to the front wall 36 of compartment 11 adjacent its bottom portion is a housing 37 containing an igniting element 38 preferably in the form of a coil.

Our construction is adapted to use a flare 16 which is the subject matter of our co-pending application for patent, Serial No. 568,152, filed December 14, 1944. Said flare 16 has a fire-proofed folded body portion 15 with a flare load of ignitable illuminating material on the inside of the folded body portion 15 and an integral hollow handle 19 and openings 50 in the front of the body portion leading to the flare load.

In use, the operator presses button 41 to motor 24, thereby operating gears 22 and moving rack 13 downwardly a notch. Fingers 30 of detents 31 fit within notches 29 and hold the flare 16 on the low shelf on a line with igniting element 38. The igniting element 38 contacts the flare load in the flare through the front openings 50 provided in the flare and ignites the load.

The operator then presses button 43 thereby closing circuit 44 and operating solenoid 45 to fire the cartridge 40 at the rear of the flare. This operates to project the flare outward from our device.

Spring switch 46 in the motor circuit operates to break the circuit and prevent the operation beyond the desired cycle.

It will be noted that there is an opening 49 in the bottom of compartment 11 to permit the lowering of the rack therethrough. Each shelf acts as a closure for the opening 49 as it descends.

Our device may be attached to a vehicle by lugs 47 and pins 48 as shown in Figs. 10 and 12. In Fig. 10 we provide a chute 55 to direct the ignited flare to a railroad track, where it can be pressed on the rail as shown in Fig. 11.

Whenever it is desired to remove the flare manually from its tube 18, button 43 need not be pressed to set circuit 44 in operation to fire cartridge 40.

Having thus described our invention, we claim:

1. A signal flare device comprising a housing having front and rear compartments, said front compartment having an opening in its bottom portion, a rack movable within said front compartment, said rack having a back and a plurality of vertically spaced shelves, a plurality of spaced barrels attached to said back, a plurality of flares, each of said flares having a folded body portion, a flare load of ignitable illuminating material attached to said body portion, and an integral hollow handle, said body portion having an opening leading to said flare load, said shelves receiving the body portions of the flares, and said barrels receiving the hollow handles of the flares, the back of said rack having a plurality of spaced openings, a pair of gears driven by a motor positioned within said rear compartment, said gears having teeth engaging said openings and move said rack downwardly through the opening in the bottom portion of said front compartment and means attached to said front compartment at its bottom portion for contacting the flare load of the lowermost flare through the opening in the body portion thereof for igniting the flare.

2. A signal flare device comprising a housing having front and rear compartments, said front compartment having an opening in its bottom portion, a rack movable within said front compartment, said rack having a back and a plurality of vertically spaced shelves, a plurality of spaced barrels attached to said back, a plurality of flares, each of said flares having a folded body portion, a flare load of ignitable illuminating material attached to said body portion, and an integral hollow handle, said body portion having an opening leading to said flare load, said shelves receiving the body portions of the flares, and said barrels receiving the hollow handles of the flares, the back of said rack having a plurality of spaced openings, a pair of gears driven by a motor positioned within said rear compartment, said gears having teeth engaging said openings and move

40

45

said rack downwardly through the opening in the bottom portion of said front compartment, a plate having a plurality of notches in its outer edges, a pair of spring detents attached to said front compartment and adapted to removably engage said notches and means attached to said front compartment at its bottom portion for contacting the flare load of the lowermost flare through the opening in the body portion thereof for igniting the flare.

3. A signal flare device comprising a housing having front and rear compartments, said front compartments having an opening in its bottom portion, a rack movable within said front compartments, said rack having a back and a plurality of vertically spaced shelves, a plurality of spaced barrels attached to said back, a plurality of flares, each of said flares having a folded body portion, a flare load of ignitable illuminating material attached to said body portion, and an integral hollow handle, said body portion having an opening leading to said flare load, said shelves receiving the body portions of flares, and said barrels receiving the hollow handles of the flares, the back of said rack having a plurality of cartridges spaced within the hollow handles of the flares, the back of the rack also having a plurality of spaced openings, a pair of gears driven by a motor positioned within said rear compartment, said gears having teeth engaging said openings and move said rack downwardly through the opening in the bottom portion of said front compartment, and means attached to said front compartment at its bottom portion for contacting the flare load of the lowermost flare through the opening in the body portion thereof for igniting the flare, and means for firing the cartridges so that the ignited flares are projected from the device.
